Primary Examiner—Mark A Goodwin(74) *Attorney, Agent, or Firm*—Banner & Witcoff, Ltd.(57) **CLAIM**

The ornamental design for a protective plate, as shown and described.

DESCRIPTION

FIG. 1 is a top view of a protective plate showing our new design;

FIG. 2 is a left side view thereof;

FIG. 3 is a front view thereof;

FIG. 4 is a right side view thereof;

FIG. 5 is a bottom view thereof;

FIG. 6 is a rear isometric view thereof; and,

FIG. 7 is a front isometric view thereof.

The broken line showing of the shafts of the hardware elements is for environmental purposes only and forms no part of the claimed design.
